UNITED STATES PATENT OFFICE.

CHARLES RIGHTER, OF PHILADELPHIA, PENNSYLVANIA, ASSIGNOR TO JOHN GAY, OF SAME PLACE.

DESIGN FOR CARPET.

Specification forming part of Design No. 7,126, dated January 20, 1874; application filed December 31, 1873.
[Term of Patent 3½ years.]

To all whom it may concern:

Be it known that I, CHARLES RIGHTER, of the city of Philadelphia, county of Philadelphia, State of Pennsylvania, have invented and produced a new and original Design for Carpets, of which the following is a specification:

The nature of my design is fully represented in the accompanying photographic illustration, to which reference is made.

I claim as my invention—
The configuration of the design hereunto annexed, when applied to carpeting.
December 13, 1873.

CHAS. RIGHTER.
